UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

DESIGN FOR ELECTRIC-LAMP SOCKET.

40,380.

Specification for Design. Patented Nov. 30, 1909.

Application filed December 5, 1908. Serial No. 466,189. Term of patent 7 years.

To all whom it may concern:

Be it known that I, REUBEN B. BENJAMIN, a citizen of the United States, residing at Chicago, in the county of Cook and State of Illinois, have invented a new, original, and ornamental Design for Electric-Lamp Sockets, of which the following is a specification, reference being had to the accompanying drawing, forming a part thereof.

The figure is a perspective view of an

electric lamp socket, showing my new design.

I claim:

The ornamental design for an electric lamp socket, substantially as shown.

REUBEN B. BENJAMIN.
